UNITED STATES PATENT OFFICE.

PHILIP DIEHL, OF ELIZABETH, NEW JERSEY, ASSIGNOR TO THE SINGER
MANUFACTURING COMPANY OF NEW JERSEY.

SEWING-MACHINE SHUTTLE.

SPECIFICATION forming part of Letters Patent No. 337,818, dated March 16, 1886.

Application filed October 8, 1885. Serial No. 179,288. (No model.)

To all whom it may concern:

Be it known that I, PHILIP DIEHL, a citizen of the United States, residing at Elizabeth, in the county of Union and State of New Jersey, have invented certain new and useful Improvements in Sewing-Machine Shuttles, of which the following is a specification, reference being had therein to the accompanying drawings.

10 My invention relates to that class of sewing-machine shuttles capable of being threaded simply by drawing the thread into slots without passing it through holes or eyes, and known in the art as "self-threading" shuttles.

15 The object of my invention is to provide a shuttle of this character which may be quickly and easily threaded, and which, while it is comparatively cheap to manufacture, is efficient in operation, and is not liable to break 20 the thread.

My shuttle is of the class known as "open-ended" shuttles, in which the bobbin is inserted at the end, and is in operation retained in the shuttle by the rear horn of the shuttle-carrier. To the upper side of the shuttle-body is attached the tension-spring, provided with two small fingers, the ends of which rest in small recesses in the shuttle-body, the rear end of said spring passing down into the inclined 25 slot, which forms an open passage from the rear end of the shuttle to the usual straight thread-delivery slot in the body of the shuttle. The rear portion of the tension-spring is held down to the shuttle-body by an offset projection at the end thereof, which springs up against the inside of the shuttle-body on the side of the said inclined slot opposite to that on which the main portion of the said spring lies, and the bend in said spring, by being engaged in said slot, holds the rear end of the 30 spring from sidewise movement on the shuttle-body.

35 In the accompanying drawings, Figure 1 is a plan view of my improved shuttle with the tension-spring in place, and Fig. 2 is a similar view with the tension-spring removed. Fig. 40 3 is a detail plan view of the tension-spring, and Fig. 4 is a rear end view of the shuttle and bobbin.

50 A denotes the shuttle shell or body, provided

with a straight thread-delivery slot, *a*, communicating with the open rear end of the shuttle-body by an inclined slot, *a'*, one side wall of which is preferably rounded at *a''*.

B is the tension-spring, which is attached at 55 its forward end to the shuttle-body by the regulating-screw *b*, said spring being provided with thread-fingers *b'* and *b''*, the points of which are bent downwardly and rest in small recesses *a''* in the top of the shuttle-body. The 60 rear end of the tension-spring is bent downwardly to form a small offset projection, *b''*, adapted to enter the inclined slot *a'* and hook up against the inside of the shuttle-body on the side of said slot opposite to that occupied 65 by the main portion of the tension-spring. The pressure of the main portion of the tension-spring and of the thread-fingers *b'* and *b''* against the shuttle-body will have a tendency 70 to lift the rear end of said spring, so that the 75 projection or hook *b''* will be held up snugly against the inside of the shuttle-body at all times, thus leaving sufficient space between the bend in said spring and the side wall of the slot *a'*, on which the main portion of the 80 tension-spring lies, to permit the bobbin-thread to be easily drawn into said slot between said bend and wall. The engagement of the downwardly-bent rear end of the tension-spring with the inclined slot *a'* serves to hold said 85 end securely in place, and as the said end extends across said slot partly on the outside and partly on the inside of the shuttle, the thread is effectively prevented from being broken by catching in said slot when the shuttle is in operation in the machine.

In threading the shuttle the thread from the bobbin C is first drawn forward into the slot *a'* beneath the tension-spring, over the thread-finger *b'*, and into the hole at the base of said 90 finger. The thread is then drawn backward over the thread-finger *b''* and into the hole at the base thereof, this latter movement bringing the thread beneath the thread-guard *b''*, and the shuttle is then threaded, as indicated 95 in dotted lines in Fig. 1.

I claim as my invention—

1. The combination, with a shuttle-body having an open inclined slot at its rear end, of a tension-spring the rear end of which ex- 100

tends across said slot partly on the outside and partly on the inside of the said shuttle-body, and rests against the inner wall of the latter, substantially as set forth.

5 2. The combination, with a shuttle-body having an open inclined slot at its rear end, of a tension-spring attached to said shuttle-body at its forward end, and provided with thread-fingers, the rear end of said spring entering 10 said slot and resting against the inner wall of the shuttle-body.

3. The combination, with the shuttle-body A, having the slots a and a' , of the tension-spring B, having the thread-fingers b' and b^2 , and the downwardly-bent projection or hook b^3 , entering the slot a' , substantially as set forth. 15

In testimony whereof I affix my signature in presence of two witnesses.

PHILIP DIEHL.
